United States Patent Office

Des. 228,733
Patented Oct. 23, 1973

228,733

EXTENDED HANDCUFF-KEY

William E. Perkins, 4910 Fauna, and Richard D. Drake,
4922 Fauna, both of Montclair, Calif. 91763

Filed May 9, 1972, Ser. No. 251,858

Term of patent 14 years

Int. Cl. D8—07

U.S. Cl. D8—136

Fig. 1

Fig. 2

Fig. 3

Fig. 4

Fig. 5

FIG. 1 is a side elevational view of an extended handcuff-key showing our new design;

FIG. 2 is an elevational view looking to the right in FIG. 1;

FIG. 3 is an elevational view looking to the left in FIG. 1;

FIG. 4 is a bottom plan view thereof; and
FIG. 5 is a top plan view thereof.

We claim:

The ornamental design for an extended handcuff-key, substantially as shown.
